APPARATUS FOR CASTING MOLTEN METAL OR OTHER FLUENT OR SEMIFLUENT MATERIAL

Application filed February 6, 1928. Serial No. 252,371.

This invention relates to a method of and apparatus for casting molten metal or other fluent or semi-fluent material irrespective of its temperature into all cavity parts of a mold 5 of simple or intricate structure so that all parts of the casting will be of maximum uniform density without the use of extraneous pressure.

In casting molten metals in sand molds and 10 also in permanent molds it is customary to pour the metal from suitable ladles into the mold at approximately the level of the inlet or sprue hole resulting in a more or less coarse grained casting and in some instances more or 15 less imperfections or deformations due to the trapping of air in the smaller parts of the mold.

Furthermore, it is well-known that these sand molds are not adapted for producing intricate 20 castings having relatively small intaglio or relief parts due primarily to the lack of sufficient pressure behind the inflowing metal and also to the fact that the sand molds are not adapted to sustain such pressure.

25 On the other hand, when casting molten metal in permanent molds under the usual practice of pouring the metal into the mold at approximately the level of the sprue hole it is found to be impracticable to produce proper 30 castings in the more intricate molds having relatively small intaglio and relief parts due to the lack of sufficient pressure behind the inflowing metal to force the molten metal into those small parts and to the trapping of gas 35 or air therein.

In the die casting process commonly employed for casting molten metal in intricate molds having relatively small intaglio and relief parts it is customary to apply extraneous 40 mechanical or air pressure behind the inflowing metal thereby increasing the number of operations necessary to produce a perfect casting and greatly increasing the cost of the casting apparatus and operation thereof due 45 to the fact that the dies are frequently large and heavy and must be constructed in such manner as to withstand the pressure to which the molten metal is subjected.

It is found, however, that the mechanical 50 or cylinder and plunger pressure mechanism

and also the air or goose neck pressure devices under the present construction are not suitable for handling molten metals with a melting point above 1500° F. due to the fact that the metal, from which the containers are 55 made, is not sufficiently strong to withstand the high air pressure of, say 200 to 500 lbs. per sq. inch, when heated above that temperature.

The main object of the present invention 60 is to be able to cast a wider range of metals and metal alloys having melting temperatures considerably above or below 1500 degrees F. under a sufficient pressure to force the metal into all, including the most minute 65 intaglio parts of any mold, without the use of extraneous pressure-producing devices and, therefore, with less labor and expense of equipment than has heretofore been practised.

In other words, I have sought to produce 70 in the mold a casting of greater homogeneity and density than has heretofore been practised by allowing the molten metal or metal alloy to fall or drop into the mold from a height sufficient to give the pressure at the 75 mold necessary to produce such homogeneity and density.

Another object is to protect the descending stream or body of molten metal from the source of supply to the mold against lateral 80 deflection or contact with adjacent objects by surrounding the same with a guard or shield extending practically the full height of the drop of the molten metal from the source of supply to the mold.

85 Another object is to provide means for controlling the flow of the molten metal from the superposed source of supply to the mold in such manner that when liberated from the melting furnace or ladle it will have an unobstructed drop to the mold, the height of the furnace, ladle or other source of supply above the level of the mold depending upon the pressure and velocity required for properly distributing the molten metal through the 90 interior of the mold.

95 Another object is to control the discharge of the molten metal from the source of supply in such manner that only the quantity required for filling the mold will be liberated.

Other objects and uses relating to the invention will be brought out in the following description.

In the drawings is represented a vertical sectional view, partly in elevation, of one form of apparatus for carrying out the various objects of the invention.

The apparatus comprehends three essential correlated steps in the casting process viz., 5 the installation, preparation and manipulation of the molds or casting machines and handling of the castings, all of which may be conducted within a relatively small space and also with a minimum amount of labor 10 at the same level or upon one floor of a building and second, the installation of the melting furnace or furnaces, melting pots or ladles, together with the preparation and reduction of the raw materials within the melting furnaces to a molten state on a superposed 15 floor of the building, and third, the liberation or release of limited quantities of the molten metal from the furnace, melting pot or ladle to drop or fall through the intervening space 20 to the sprue holes of their respective molds for producing the desired castings therein, the height or head-drop of the molten metal from the source of supply of the mold depending somewhat upon the quality of the metal 25 and also upon the capacity of the mold, but in all cases will be sufficient to give the velocity and pressure required at the mold to produce a casting of maximum density and homogeneity.

30 As illustrated, the mold —1— of any desired form, size or capacity is supported upon a suitable base or pedestal —2— at a height most convenient for manipulation thereof, the pedestal —2— being mounted upon a sub-base or floor —A— of the building in 35 which the apparatus is located.

The mold —1— is preferably made in sections capable of being separated any desired extent to permit the discharge or removal of 40 the casting previously made therein and, when assembled for the reception of the molten material, the sections will be firmly locked together by any well-known locking means commonly used in metal molds.

45 Any suitable means may be provided for opening and closing the mold sections, said means consisting, in this instance, of opposed levers —3— pivoted or fulcrumed at —4— on suitable standards —5— and operatively 50 connected to their respective sections by links —6— whereby the vertical movement of the levers in opposite directions will open and close the sections of the mold along and upon its supporting base —2—.

55 The parts thus far described constitute what may be termed a casting machine and obviously a large number of these machines may be similarly installed in more or less close juxtaposition upon the same floor so 60 that they may be conveniently operated with-

out in any way interfering with the handling of the raw materials and charging and discharging of the melting furnaces, pots or ladles.

The means for reducing the raw materials 70 to molten metal is preferably mounted upon a superposed floor or other support —A'— of the building as nearly as possible directly over the casting machines on the lower floor and, as illustrated, comprises, in this instance, a cupola or melting furnace —7— mounted in a suitable frame work —8— some distance above the floor —A'—, said melting furnace being provided with a hopper-shaped bottom having an outlet —9— controlled by a suitable gate or valve —10—.

A measuring pot or ladle —11— is supported in any suitable manner directly below the discharge opening —9— of the furnace to receive a limited quantity of the molten metal 85 therefrom when the gate or valve —10— is opened, said measuring pot or ladle —11— being provided with an outlet —12— which is controlled by a valve or gate —13— similar to the gate —10—.

90 The capacity of the pot or ladle —11— is approximately equal to the capacity of the mold as —1— into which the molten metal is to be discharged therefrom.

The outlet of the pot or ladle —11— is preferably disposed in vertical alignment with the sprue hole as —14— of the mold so that when it is desired to produce a casting in said mold the gate —13— controlling the outlet —12— of the ladle —11— will first be closed after 100 which the gate —10— controlling the outlet of the furnace —7— will be opened to allow the molten metal to flow into the pot or ladle —11—.

105 After a suitable quantity of the molten metal has been allowed to flow into the pot or ladle —11— the gate —10— will be closed and the gate —13— opened thereby allowing the molten metal to drop directly into the inlet or sprue hole of the mold —1—.

110 The outlet of the measuring pot or ladle —11— is connected to the inlet of the mold by means of a vertical tubular guard —15— of sufficient interior capacity or diameter to allow the molten metal to drop or fall there-through without adhering to the walls thereof, the purpose of said guard tube being to prevent material reduction of the temperature of the molten metal in transit from the source of supply to the mold and also to prevent lateral deflection of said molten metal from a straight vertical drop from the source of supply to the mold and incidentally preventing contact of external objects with the descending stream or body of molten metal.

115 The walls of the tubular guard —15— are preferably hollow to form an intervening chamber —16— which may be an air or vacuum chamber for heat-insulating purposes or 120 may be filled with a heating medium to fur-

ther reduce the liability of reduction of the temperature of the molten metal in transit from the source of supply to the mold.

The outlet in the lower end of the guard tube —15— adjacent the mold —1— may be controlled by a suitable gate or valve —17— to be closed when the mold is being manipulated preparatory to the reception of the molten metal but will be opened as soon as the mold sections are properly placed for receiving the molten metal, said gate being operated by means of a hand lever —18— mounted on the base —2—.

The walls of the measuring pot or ladle —11— may also be hollow to form an air or vacuum chamber —19— or for receiving a heating medium to prevent the reduction of the temperature of the molten metal therein.

Suitable pipes —15'— and —19'— are connected respectively to the chambers —15— and —19— to be used either for withdrawing the air from or supplying a heating agent to said chambers.

The gates —10— and —13— controlling the inlet and outlet of the molten metal to and from the measuring pot or ladle —11— are adapted to be operated by separate levers —20— and —21— mounted on the frame —8— within convenient reaching distance of the operator or furnace attendant of the floor —A'— but, in some instances, it may be desirable to control these levers from the lower floor —A— and, for this purpose, they are provided with pendant operating rods —20'— and —21'— respectively, extending downwardly through openings in the floor —A'— to levels within convenient reaching distance of the operators on the lower floor —A—.

It will be understood from the foregoing description that the apparatus shown is mainly diagrammatic and is intended only as illustrating a simple means for carrying out the casting process by elevating the source of supply for the molten metal a sufficient distance above the mold and in such relation thereto that when a charge of the molten metal is released from the source of supply it will enter all of the intaglio parts of the mold with sufficient force, velocity and pressure to produce a more homogeneous and denser casting than has heretofore been practised in any known pouring process and at the same time eliminates the cumbersome mechanisms involved in the use of cylinder and plunger type or air pressure type of die casting machines.

Furthermore, under this construction and process the melting furnaces and handling of all raw materials is done on a separate floor a considerable distance above the casting floor so that the heat radiated by the furnaces on the upper floor does not have any inconvenient effect upon the temperature of the lower or casting floor which is also free from accu-

mulations and handling of the raw materials thus permitting a more expeditious and economical operation of the casting machines than has heretofore been practised.

It will also be noted that under this construction practically all of the devices for controlling the discharge of the molten metal from the source of the supply to the measuring pot and from the measuring pot to the molds, together with the operating devices for the mold sections may be controlled from the same floor on which the casting machines are placed.

The upper end of the shield or guard tube —15— is supported upon suitable posts —22— on the upper floor —A'— through the medium of adjusting screws —23— which permits the guard tube to be adjusted vertically.

The measuring pot or ladle —11— is removably supported upon the upper end of the guard tube —15— to permit the use of ladles of different capacities and may be raised and lowered with the guard tube by the adjustment of the screws —23— to permit its removal and replacement and also to adjust it in proper alinement with the outlet of the measuring furnace and inlet of the guard tube.

The lower end of the guard tube is provided with a nozzle —24— which may be removed when necessary to permit the opening therethrough to be cleaned from any material which may adhere to the walls thereof.

A gate or valve —25— is movable in the lower end of the guard tube —15— to control the flow of the molten metal therethrough and to serve as an additional safety means for preventing the discharge of molten metal from the interior thereof particularly during the removal of the nozzle.

Operation

The container for the molten metal to be used in making the casting will be supported in a plane a considerable distance above the mold which is to receive the molten metal to form an intervening air space through which the molten metal must travel in transit from the container to the mold, but it is obvious that this space will necessarily vary according to the quality of the metal and size or intricacies of the mold, but in all cases will be sufficient to cause an appreciably greater velocity of travel of the molten metal when entering than when leaving the container so as to obtain the necessary head-pressure and velocity for driving the molten metal into all parts of the mold.

The capacity of the container, such, for example, as the ladle being approximately equal to the capacity of the molds, it follows that when the charge from the ladle is released it will travel in a more or less cohesive body through the intervening space

with gradually increasing velocity or momentum so as to enter the mold at a far greater velocity than when leaving the container which has the effect of forcing the molten material into all parts of the mold.

5 During the reduction of the metal to a molten state ready for casting within the melting furnace or cupola —7— the gate or valve —10— will remain closed and when the mold 10 and other parts of the apparatus are all set ready for casting the gate or valve —13— in the outlet of the measuring pot or ladle —11— and also the gates in the lower end of the guard tube —15— and nozzle —24— will be 15 closed. Then, when it is desired to produce the desired casting in the mold, the valve —10— in the outlet of the melting furnace will first be opened to allow the molten metal to fill the measuring pot or ladle —11— 20 whereupon said valve will be closed and the gates —13—, —17— and —25— in the measuring pot and guard tube will be instantly opened to allow the casting charge to drop through the intervening space into the mold 25 and in view of the accelerated speed of this charge as it enters the mold it is evident that its velocity and weight will force the metal under relatively high pressure into all of the intaglio parts of the mold to complete the 30 casting and as soon as the casting is sufficiently set or hardened the sections of the mold may be separated by any suitable means to permit the casting to be withdrawn.

The mold sections may then be replaced 35 and the various gates or valves manipulated to repeat the operation just described.

As previously stated, the apparatus and process are particularly simple, expeditious and highly efficient as compared with the apparatus and processes now in common use 40 and greatly increases the output for a given period of time with a minimum expenditure of time and labor.

An important result of dropping the 45 molten metal from an appreciable height through the guard tube and into the mold is that the gases and vapor from the molten metal are allowed to escape to atmosphere in transit through said space so that molten metal entering the mold is substantially pure 50 or free from such gases and vapor, and, therefore, has a far greater density and homogeneity than would be possible if the gases and vapor were retained in the molten metal 55 when filling the mold.

What I claim is:—

1. In an apparatus for casting molten metal in a mold having a sprue, a measuring pot 60 having a capacity approximately equal to that of the mold and provided with an inlet in its top and an outlet in its bottom, separate gates controlling the inlet and outlet, and an upright conduit having a straight vertical 65 passage therethrough leading directly

from the outlet of the measuring pot to the sprue of the mold.

2. In an apparatus for casting molten metal in a mold having a sprue, an upright conduit having a straight vertical passage therethrough discharging at its lower end directly into the sprue of the mold and its upper end of sufficient height to cause the momentum of the molten metal admitted thereto and passing through said passage to drive 75 said molten metal into all parts of the cavity of the mold, and means for limiting each charge of molten metal admitted to the upper end of said passage to about the capacity of the mold to enable the entire charge to be 80 precipitated as a unit into the mold.

3. In an apparatus for casting molten metal in a mold having a sprue, an upright conduit having a straight vertical passage therethrough, a nozzle secured to the lower end of the conduit to form a continuation thereof and having its lower end adapted to discharge directly into the sprue of the mold, a container for the charge of molten metal discharging directly into the upper end of 85 said passage and having a capacity substantially equal to that of the mold, and a valve controlling the discharge of the molten metal from the container into said passage and adapted when opened to permit the precipitation of said charge from the container into 90 the mold.

· In witness whereof I have hereunto set my hand this 23d day of January, 1928.
